UNITED STATES PATENT OFFICE

HENRY LOUIS FARMER, OF TEWKSBURY, MASSACHUSETTS

CURLING IRON SUPPORT

Application filed October 30, 1938. Serial No. 316,024.

This invention relates in general to supports and more particularly has reference to a rack for a curling iron.

While the holder forming the subject matter of this invention is intended primarily for use with the electrical irons now generally found on the market, it will be apparent from the following description that the same is adaptable as well to the prior type of irons heated by contact with a flame.

It is well known that when electrical curling irons of the ordinary construction are permitted to stay in connection with an electrical socket after reaching the temperature required for curling hair, they are liable to become overheated, and if thoughtlessly placed on a piece of furniture or other object, scorching of the same may result. Very often, conflagrations have been traced to curling irons thus carelessly mislaid.

While this danger is not encountered to the same degree in the old type of irons in which the heat gradually diminishes after the iron has been withdrawn from the flame, it nevertheless is apt to scar surfaces or burn holes in fabrics in the same manner.

It has been sought in the past to construct holders of the type where the iron is laid across projecting arms, but it is manifest that a support of this type does not afford a positive fixture, and unless carefully placed the iron is in danger of falling off. In the same manner, supports have been provided which are of the same or relatively equal weight as the curling iron, and inasmuch as they have been designed to receive the iron on an arm projecting from the base, it is manifest that unless care is exercised the support may fall over. Also, in the event of defective connections, the heat may be transmitted through the iron to the supports; nor have such structures presented an ornamental appearance.

The usual connections for receiving the plugs attached to the usual cords on the irons are not always conveniently placed and hence difficulty is often experienced in turning on and off the current by removal and insertion of the plug. Also, the cord when unattached is difficult to conveniently arrange on a dressing table or the like and the plug at the end is

seldom at hand for insertion in a connecting fixture. In the event of a defective connection, if the plug has not been wholly withdrawn but to all appearances is disconnected, if the current is still running through the iron, dangerous results may obtain unless care has been exercised in placing the iron on a surface not affected by heat.

An object of this invention is to provide a rack having a support for a curling iron adapted to maintain the iron out of contact with the surface upon which the base of the rack is laid.

Another object of this invention is to provide a rack having a support for a curling iron, with a base insulated from the support carrying the iron so that no heat can be transmitted through the support to the base.

Still another object of this invention is to provide a rack having a support for a curling iron adapted to prevent contact of the iron with the rack.

Still another object of this invention is to provide a rack having a support for an electrical curling iron designed to hold the iron out of contact with the rack and the surface upon which it is laid, and hold the plug when the iron is disconnected.

A further object of this invention is to provide a rack having a support for a curling iron properly weighted so that the weight of the iron cannot tip the rack.

A still further object of this invention is to provide a rack for a curling iron having a switch mechanism included in the base for connection with the iron and a source of current and an indicator located in the support in connection with the switch mechanism, so that the heating of the iron may be controlled in the base and the passage of current to the iron observed.

A still further object of this invention is to provide an ornamental rack for an electric curling iron having an ornamental figure designated to hold the iron and the plug when the iron is disconnected.

With these and other objects in view which may be incident to my improvements, the invention consists in the parts and combinations to be hereinafter set forth and claimed,

with the understanding that the several necessary elements comprising my invention may be varied in construction, proportions and arrangement without departing from the spirit and scope of the appended claim.

In order to make my invention more clearly understood, I have shown in the accompanying drawings means for carrying the same into practical effect, without limiting the improvements in their useful applications to the particular constructions which for the purpose of explanation have been made the subject of illustration.

In the drawings forming a part of this specification:

Figure 1 is a side view of the ornamental rack for supporting a curling iron forming the subject matter of this invention.

Figure 2 is a front view of the rack shown in Figure 1.

Figure 3 is a top fragmentary view of the tail fin of the mermaid forming the support.

Figure 4 is a fragmentary perspective view of the arm of the mermaid shown with the elliptical ring in her hand.

Figure 5 is a front view of the mermaid showing the slanting of the ring in her hand to allow vertical positioning of the curling iron.

Figure 6 is a sectional view of the base shown in Figure 1 showing a switch mechanism included in the rack.

Figure 7 is a sectional view of the base shown in Figure 1 showing a switch mechanism and current indicating device included in the base.

Figure 8 is a side view of a modified form of the support shown in Figure 1.

Referring more particularly by numerals to the drawings, in which the same and similar elements are designated by like symbols of reference throughout, and more especially to Figure 1, there is shown the curling iron rack forming the subject matter of this invention comprising a hollow base 1 preferably stamped out of any suitable metal.

The base 1 is formed in the shape of a rock 2 with imitations of billows 3 breaking against the same.

A figure 4 simulating a mermaid is mounted on the top of the base. While it is manifest that any other ornamental figure may be employed in place of that shown, or an ordinary support such as will be later described, inasmuch as the rack is intended to hold a curling iron the mermaid, being suggestive of caring for the hair, is deemed preferable, particularly as the figure, as will be later understood, is well adapted for this purpose.

The support 4 is secured on the base by a bolt 5 suitably connected to the mermaid's body and fixed inside the base by a nut 6. The body of the mermaid is separated from the base by a washer 7 composed of any

suitable non-conductive material, and the nut 6 from the interior of the base by a similar washer 8 and an ordinary metal washer 9. To complete the insulation, the portion of the bolt 5 passing through the aperture in the top of the base is separated therefrom by an insulated collar 10.

The bottom of the base 1 is preferably formed with an inwardly projecting rim 11 to which there is secured a plate of insulating material 12 by a series of screws 13. The insulating material 12 may be the same as that used for the washers 7 and 8, preferably asbestos, although it will be apparent that a number of other materials such as hard rubber will serve the same purpose. If the bottom of the base is covered with asbestos, however, the mat will tend to prevent injury to any surface upon which the rack is laid, as well as serve to insulate the same from any heat contained in the base.

The insulation between the mermaid and the base is provided to guard against the transmission of heat in the event of exchange between the heated iron and the mermaid and likewise the insulation on the bottom in the event of a defective connection between the support and the base or a short circuit in electrical mechanism to be herein-after described.

The mermaid's arm, as shown in Figure 1, is upwardly bent as at 14 and a ring 15, as shown in Figures 4 and 5, mounted in her hand. It is to be noted that the ring is elliptical in shape and when mounted in the hand is slanted at an angle to the horizontal. It is intended that an ordinary curling iron 16 having the usual movable portion 17 operated by an arm 18 be inserted therein. It is deemed preferable to weight the tail of the mermaid to compensate for the weight of the iron, so that the rack will not be tipped over when the iron is inserted through the ring. The shape and mounting of the ring permit the vertical positioning of the iron as shown in Figure 5, in that it accommodates the angular arm 18.

With reference to Figure 3, the tail fin on the mermaid is cup shaped to seat the conventional plug 20 and provided with a slit 21 to accommodate a usual cord 22 for connecting the iron and the plug. In this manner, it will be appreciated that when the iron is not in use it may be inserted through the ring 15 and the cord 22, which usually presents an untidy appearance, properly positioned by resting the plug 20 in the cup 19 on the tail of the figure.

Another type of rack is shown in Figure 8, wherein a plain base 23 is provided having the insulating mat 12 at the bottom and the insulating washer 7 at the top. A support 24 is mounted in the same manner as described with reference to the Figure 4 on the base and

similarly secured. The ring 15 is secured in the end of the support corresponding to the hand of the mermaid, and a cup 25 similar to the tail of the mermaid fixed on the other 5 end. The support 24 is provided with a portion of enlarged dimensions 26 or a weight attached at this point to compensate for the weight of the iron when it is inserted in the ring and thus prevent tipping over the rack 10 when the iron is inserted.

In Figure 6 there is shown a modified form 15 of iron in which the cord 22, instead of passing directly from the plug 20 to the iron 16 passes through the base 1 of the rack. In this form, the base is provided with oppositely disposed apertures in which are inserted collared sleeves 27 and 28 for receiving the cord. An ordinary throw switch mechanism 29 is mounted in the top of the base adjacent 20 an aperture 30 adapted to allow operation of a switch lever 31. The switch is connected to the cord through a conductor 32 inside the base. In this manner, the plug 20 attached to the end of the cord 22 may be permanently 25 connected to a source of current and heat the iron, connected to the end of the cord controlled from the base by operation of the switch lever 31.

In Figure 7 there is shown a form of base 30 in which an aperture is provided on the face of one of the billows enclosed by a piece of transparent material 33, preferably colored glass. A flange 34 is mounted in the base below the aperture adapted to receive a conventional light bulb 35 connected to the cord 22 between the switch and the curling iron. Thus, when the iron is heating, the bulb will be lighted and the passage of current observed by the coloring of the glass 33. It 35 is manifest that in employing the construction shown in either Figures 6 or 7, if the plug is disconnected it may be attached to the tail in the same manner as described with reference to Figure 1.

40 There is accomplished by this invention a rack for a curling iron in which an ornamental figure is provided to hold the iron and plug attached to the cord, and in which the heating of the iron may be controlled and observed, the same being adapted to maintain the iron in a vertical position out of contact with the rack and the surface upon which it is laid with insulation provided on the bottom of the base and between the base and the support to prevent transmission of heat in the event of defective connections. 45

50 While I have shown and described the preferred embodiment of my invention, I wish it to be understood that I do not confine myself to the precise details of construction herein set forth, by way of illustration, as it is apparent that many changes and variations may be made therein, by those skilled 55 in the art, without departing from the spirit

of the invention, or exceeding the scope of the appended claim.

I claim:

A support for a curling iron comprising, a hollow base having a transparent portion, 70 insulating means secured to the bottom of said base to prevent the transfer of heat, a support attached to the upper part of said base, a strip of insulating material between said support and said base, a ring carried by 75 said support on one end to hold the curling iron, a weighted extension carried by the support opposite said ring to compensate for the weight of the curling iron, said weighted extension being slotted to hold the plug of the curling iron, a switch mechanism mounted in the base and illuminating means within 80 said base connected between the switch and the curling iron to indicate through the transparent portion of the base whether the 85 curling iron is being heated.

In testimony whereof I affix my signature.

HENRY LOUIS FARMER.
